TABLE LEG

Morton R. Cohen, Chicago, Ill.

Application March 11, 1957, Serial No. 45,193

Term of patent 14 years

(Cl. D33—14)

Fig. 1 is a perspective view of a table leg showing my new design.

Fig. 2 is an elevational view of the same on an enlarged scale;

Figs. 3 and 4 are sectional views taken along the lines 3—3 and 4—4 of Fig. 2 respectively;

Fig. 5 is a fragmentary view of the leg showing the brace in its association with the inner surface of said leg.

The dotted lines shown in Figs. 1 and 2 are for illustrative purposes only.

I claim:

The ornamental design for a table leg, substantially as shown and described.
